UNITED STATES PATENT OFFICE.

FREDERICK T. ELLITHORPE, OF NEWARK, NEW JERSEY.

AUTOMATIC SAFETY DEVICE FOR ELEVATORS.

SPECIFICATION forming part of Letters Patent No. 535,096, dated March 5, 1895.

Application filed December 17, 1894. Serial No. 532,082. (No model.)

To all whom it may concern:

Be it known that I, FREDERICK T. ELLITHORPE, a citizen of the United States, residing at Newark, in the county of Essex and State of New Jersey, have invented certain new and useful Improvements in Automatic Safety Devices for Elevators; and I do declare the following to be a full, clear, and exact description of the invention, such as will enable others skilled in the art to which it appertains to make and use the same.

My invention relates to improvements in automatic safety devices for elevators; and it has for its general object to provide cheap, simple, and efficient means, adapted, when the car has attained a dangerous speed, to automatically apply the brakes so as to stop the car and avert a casualty.

Other objects and advantages of the invention will be fully understood from the following description and claims when taken in connection with the annexed drawings, in which—

Figure 1, is a front elevation, partly broken away, of an elevator equipped with my improvements. Fig. 2, is a horizontal section on the line α , α , of Fig. 1. Fig. 3, is an enlarged, detail section on the line α , α , of Fig. 2. Fig. 4, is an enlarged, perspective view of one of the keeper members and the beveled or inclined block connected therewith. Fig. 5 is a side elevation of the elevator, and Fig. 6 is an enlarged detail section.

In the said drawings similar letters designate corresponding parts in all of the several views, referring to which—

A, indicates the ways or guides of an elevator.

B, indicates the car.

C, indicates castings connected to the car and having slides a , adapted to engage the guides or ways A, and also having portions b , adapted to rest and move at one side of said guides or ways.

D, indicates brake shoes adapted to engage the guides or ways A.

E, indicates levers which are connected at their outer ends to the brake shoes and have their inner ends connected by an equalizing bar or link F.

G, indicates a wheel mounted on the equalizing bar or link.

H, indicates a cam lever engaging and adapted to transmit movement to the wheel G; and I, indicates a spring which is connected to the cam-lever H, and the wheel G, as better shown in Fig. 6, and is adapted to return said wheel and the parts connected therewith to their normal positions when the cam lever is lowered.

The lever H, is connected with a weight J, mounted in a frame K, by a cable L, which has one end connected to the car as indicated by c, and takes around a sheave x^7 , (see Fig. 5,) carried by the weight J, and around several sheaves arranged at the top of the elevator shaft; and the said cable is normally held so as to prevent the weight J, from raising the lever H, and applying the brakes, by the keeper M, which is designed and adapted to hold a button or enlargement N, on the cable as shown in Fig. 1, of the drawings. The said keeper M, comprises two members P, Q, and the member P, is connected by a rod d, as illustrated, with a lever R, arranged in the car within convenient reach of the attendant whereby it will be seen that the said attendant is enabled to quickly move the keeper member P, so as to release the cable and effect an application of the brakes.

By reason of the mechanism thus far described, which is fully and clearly disclosed and claimed in another application for Letters Patent, bearing even date herewith, and serially numbered 532,081, it will be seen that when the car attendant moves the lever R, as before described, the button N, of the cable will be released from the keeper M, when the weight J, tending to move downwardly will raise the lever H, and said lever through the medium of the wheel G, equalizing bar or link F, and the levers E, will press the brake shoes D, against the ways or guides A, and thereby stop the car.

It often happens that when the car runs away or attains a dangerous speed, there is not time for the attendant to effect an application of the brakes, and it is therefore highly desirable that the car should be equipped with some means for automatically applying the brakes when the car attains a dangerous speed. To this end, I connect a beveled or inclined block S, which preferably has anti-friction rollers on its face, with the keeper

member Q, which is fulcrumed in a suitable bracket T, as shown, and provide a vertically-movable, beveled or inclined block U, to engage the block S. This block U, is carried by 5 a sleeve V, which is loosely mounted on the shaft e, of a centrifugal governor W, and is connected with the arms f, of said governor by links g, as shown; and it will therefore be seen that when the governor is rotated at a 10 high rate of speed, and its arms f, are raised, the sleeve V, and the block U, will also be raised, and the beveled or inclined face of the latter engaging the corresponding face of the block S, will move said block in the direction 15 indicated by arrow (see Fig. 1), and in consequence will swing the keeper member Q, on its fulcrum so as to release the cable L, and effect an application of the brakes.

The governor W, is suitably arranged on 20 the car (preferably in the manner shown); and in order that it may be rotated at a speed corresponding to the speed of the car, its shaft e, is provided at its lower end with a beveled gear h, which meshes with a beveled gear i, 25 on a shaft j. (See Fig. 3.) This shaft j, is also provided with a wheel k, and it is designed and adapted to be rotated when the car is in motion through the medium of the cable X, which has its opposite ends connected to the car and is shown as taking 30 around a sheave l, at the top of the elevator shaft, around the wheel k, on the shaft j, around a second sheave m, carried by the car and around a sheave n, carried by a weight p, 35 which weight is designed to take up slack of the cable and keep it taut at all times. By this construction it will be perceived that as the car runs up and down, the cable X, through the medium of the mechanism described, will 40 rotate the governor at a speed corresponding to that of the car, and when the car attains a dangerous speed, the governor will rotate at a high speed which will result in the arms f, being raised and the brakes being applied, as 45 before described.

In some cases the manual devices for effecting an application of the brakes may be omitted, in which case the keeper member P, might be made fixed, but I generally prefer 50 to equip a car with both the manual and automatic devices so that if one fails to effect an application of the brakes when necessary, the application may be effected by the other.

It will be seen from the foregoing that while 55 very cheap, simple and compact, my improved automatic mechanism is very reliable and positive in its action and will surely effect a release of the cable and a consequent application of the brakes when the car attains a 60 dangerous speed.

I do not desire to be understood as confining myself to placing my improved safety devices upon the top of the elevator cars, nor do I desire to be understood as limiting myself 65 to using the devices upon elevator cars as they may be used to advantage upon inclined tramway and other cars.

Having described my invention, what I claim is—

1. In an elevator safety device, the combination of a keeper adapted to be arranged on a car and having a movable member, a block S, connected with the movable member of the keeper and having a beveled or inclined face, a movable block U, having a beveled or inclined face engaging that of the block S, means for moving the block U, a brake shoe and means whereby the brake shoe is thrown into operation when the movable member of the keeper is moved substantially as and for 80 the purpose specified.

2. In an elevator safety device, the combination of a keeper adapted to be arranged on a car and having a movable member, a block S, connected with the movable member of the keeper and having a beveled or inclined face, a movable block U, having a beveled or inclined face engaging that of the block S, a centrifugal governor connected with the block U, means for rotating said governor, a brake 90 shoe and means whereby the brake shoe is thrown into operation when the movable member of the keeper is moved substantially as and for the purpose set forth.

3. In an elevator device, the combination 95 of a keeper adapted to be arranged on a car and having a movable member, a block S, connected with the movable member of the keeper and having a beveled or inclined face, a block U, having a beveled or inclined face engaging 100 that of the block S, a governor connected with the block U, a wheel k, connected with the governor a cable engaging with the wheel k, and adapted to cause the same to rotate as the car moves up or down, a brake shoe, and 105 means whereby the brake shoe is thrown into operation when the movable member of the keeper is moved substantially as and for the purpose set forth.

4. In an elevator safety device, the combination of a keeper adapted to be arranged on a car and having a movable member, a block S, connected with the movable member of the keeper and having a beveled or inclined face, a governor comprising a shaft, centrifugal 115 arms f, and a sleeve loosely mounted on the shaft and connected with the centrifugal arms, a block mounted on the sleeve of the governor and having a beveled or inclined face engaging that of the block S, a suitable means for 120 rotating the governor, a brake shoe, and means whereby the brake shoe is thrown into operation when the movable member of the keeper is moved substantially as and for the purpose set forth.

5. In an elevator safety device, the combination of a movable device adapted to hold a cable, the said cable connected with a weight, a block S, connected with said device and having a beveled or inclined face, a movable 130 block U, having a beveled or inclined face engaging that of the block S, a brake shoe connected with the cable and means for moving the block U, so as to transmit motion to

the block S, and the cable holding device, and release the cable, substantially as specified.

6. In an elevator safety device, the combination of a car, a keeper arranged on the car and having a movable member, a block S, connected with the movable member of the keeper and having a beveled or inclined face, a governor comprising a shaft having a bevel gear *h*, centrifugal arms *f*, and a sleeve loosely mounted on the shaft and connected with the centrifugal arms, a block mounted on the sleeve of the governor and having a beveled or inclined face engaging that of the block S, a shaft *j*, having a bevel gear engaging the

gear on the governor shaft and also having a 15 wheel *k*, the weight *p*, carrying a sheave *n*, the cable connected at opposite ends to the car and taking around the several sheaves *k*, *l*, *m*, *n*, a brake shoe, and means whereby the brake shoe is thrown into operation when the 20 movable member of the keeper is moved substantially as and for the purpose set forth.

In testimony whereof I affix my signature in presence of two witnesses.

FREDERICK T. ELLITHORPE.
